DRILL SHARPENING DEVICE

Joseph Adrian, Cleveland, Ohio, assignor to Super Speed Printing Machinery, Inc., Cleveland, Ohio, a corporation of Ohio

Application October 15, 1948, Serial No. 54,638

2 Claims. (Cl. 76—82)

1

This invention is an improved drill sharpening device that is adapted to be placed upon the work supporting table of a drilling machine and by means of which the drill may be sharpened without its being removed from the machine. Inasmuch as drills have to be sharpened frequently, considerable time is saved by the use of my invention since it becomes unnecessary to suspend operation of the machine for the purpose of removing and replacing the drills.

The device is intended for use especially with paper drilling machines wherein hollow drills are employed, and more especially with the paper drilling machine that constitutes the subject matter of my copending application Serial No. 52,019, filed September 30, 1948.

In the machine just referred to, provisions are made for manually rotating the drill in a particularly convenient manner; and, like most others of prevailing type, the machine incorporates a pressure plate for holding the work down against the work supporting table.

A primary object of my invention is to provide a simple and relatively inexpensive device of the aforesaid character that is highly efficient; that is especially convenient of use, and by which the human element is practically entirely removed from the drill sharpening operation so far as pressure between drill and tool is concerned. According to my invention, the pressure of the tool upon the drill is substantially constant and uniform thereby to insure against roughness and irregularity of the cutting edge of the drill.

Another object of the invention is to provide a drill sharpening device composed of few parts that are so designed and related as to facilitate assembly and disassembly, and to expedite the removal and replacement of the sharpening tool when such becomes necessary.

A further object of the invention is to provide a drill sharpening device that is substantial and durable and practically immune from disorder.

The foregoing objects, with other and more limited ones hereinafter appearing, are attained in the embodiment of the invention illustrated in the accompanying drawing wherein like reference characters designate like parts throughout the several views.

In the drawing, Fig. 1 is a fragmentary side elevational view of a paper drilling machine, including a part of the work supporting table whereon my improved drill sharpening device is positioned with the sharpening tool engaged by the drill and with the pressure plate of the machine bearing upon an abutment of the device; Fig. 2 is a perspective view of the device, and Fig. 3 is a vertical section through the same in the common plane of the axis of the tool carrying member and of the stop screw.

2

The drill sharpening device, designated generally by the reference numeral 1, includes a body portion 2 that rises from a base 3, the support-engaging under surface 4 of which is flat and in a plane normal to the axis of the body portion 2. The base desirably is formed of two substantially semi-circular portions whose centers are coincident with the axis of the body portion 2. Rising from the base along one side of the body portion and extending a suitable distance thereabove is an abutment 5. The foregoing elements are desirably parts of an integral casting.

The body portion 2 has an axial cylindrical recess 8 that opens through the upper end of said portion and the bottom wall 9 of which is within the plane of the base 3. Slidable within the recess 8 is a cylindrical member 10. Axial sockets open through the opposite ends of the member 10, and connecting said sockets is an axial bore 13. The head of a drill sharpening tool 15 occupies the socket in the upper end of the member 10 while the shank 16 of said tool projects through the bore 13 into the socket in the lower end of said member. The tool is held against movement with respect to the member by a set screw 17 that is threaded into a radial tapped hole in the member 10.

A helical spring 11 is compressed between the bottom wall 9 of the recess 8 and the opposed end wall of the socket in the lower end of the member 10, and tends to retain the member 10 in elevated position with a shoulder 19 thereof in engagement with stop means 20, under which circumstances the upper end of the member 10 is desirably flush with the corresponding end of the body portion 2. The stop means 20 is preferably formed by the head of a screw 21 that is threaded into a tapped hole in the body member. Said hole is closely adjacent and parallel to the recess 8, and the head of the screw occupies a counterbore 22 which has its major part in the body portion 2 but extends over into the member 10 thereby to provide a shallow longitudinally extending groove and, at its lower end, the previously mentioned shoulder 19. The stop means 20, by projecting into said groove, serves the double purpose of limiting the upward movement of the member 10 and holding said member against rotation with respect to the body portion 2.

Fig. 1 shows the drill sharpening device 1 in position on the work supporting table T of a drilling machine designated generally by the reference letter M. This machine is fully described in my aforesaid application, and includes a vertically movable head H by which a pressure plate P is yieldingly supported through a rod p' that reciprocates within a vertical hollow boss h'. The pressure plate is depressed by a spring p² that

is compressed between the hub of said plate and the underside of the boss h' .

D is a hollow drill, connected in the usual manner to a drill spindle h^5 that is journaled in the head H and has a pulley h^6 secured to its upper end. A belt h^7 extends about this pulley and one designated h^8 on the upper end of the shaft h^9 of a motor designated h^{10} that is carried by the head H. Also fixed to the motor shaft is a fly wheel h^{11} .

The head H is guided for vertical movement on a column C, and a so-called return spring S that surrounds said column tends to retain the head in elevated position. By suitable means, not shown herein but fully revealed in my former application above referred to, the head is adapted to be depressed against the action of the spring S.

In the use of the device, the pressure plate P is lifted and the device is placed upon the table T with the tool 15 approximately aligned with the drill D. Now, by the means referred to, the head H is lowered to engage the hollow drill D with the pointed end of the tool. By a camming reaction between the drill and tool (provided the parts are out of alignment), the device will be shifted until the tool is centered in the drill and, by continued movement of the head, the tool and its carrying member 16 will be depressed against the action of the spring 14, but preferably only to a slight degree as may be indicated by the distance the upper end of the member 16 is below the corresponding end of the body portion 2. The predetermined tension of the spring 11 is such as will produce a proper pressure of the tool on the drill when the member 16 is depressed to the extent mentioned. In the positioning of the device upon the table, the abutment 5 is located beneath the pressure plate P, and now with the tool properly aligned with the drill, the device may be held in place upon the table by releasing the pressure plate and allowing it to bear on the abutment 5 under the full force of the spring p^2 . The operator may now reach over the table of the machine and grasp the fly wheel h^{11} and, through the previously described driving connections, rotate the spindle h^5 and consequently the drill D relative to the stationary tool 15. A few turns of the drill will be sufficient to sharpen it, and since the tool bears with constant pressure against the end of the drill, the action of the tool upon the drill will be uniform throughout the circumference of the latter, thereby producing a smooth and even cutting edge. After the drill has been sharpened, it may be retracted by elevating the head H so as to lift the lower end of the drill above the point of the tool 15, after which the pressure plate may be raised and the device removed from the machine.

As shown in my application aforesaid, a guard encloses the machine head and motor, together with the driving connections between the motor and the drill spindle, etc., but said guard has an opening through which the fly wheel h^{11} is readily accessible at all times.

Having thus described my invention, what I claim is:

1. A drill sharpening device comprising a flat base, a body portion extending from the base with its axis normal to the plane thereof, said body portion having an axial cylindrical recess that opens through its upper end and the bottom wall of which is approximately in the plane of the base, a cylindrical member slidably fitting said recess, said member having axial sockets in

its ends and an axial bore connecting said sockets, a drill sharpening tool having a head that occupies the socket in the exposed end of said member and a shank that projects through the said bore, the member having a radially disposed threaded hole that opens into said bore, a set screw threaded into said hole for engagement with the shank of the tool, a helical spring compressed between the bottom wall of the recess and the end wall of the socket in the adjacent end of said member, a threaded hole in the body portion in substantially parallel and closely spaced relation to the recess, the outer end of said hole being enlarged by a counterbore that opens through the end of the body portion remote from the base and laterally through the adjacent wall of the recess, the contiguous portion of the aforesaid member containing a part of said counterbore thereby to provide in said member a longitudinal groove and a shoulder at the bottom thereof, and a screw threaded into said hole of the body portion and having a head extending into said groove and overhanging said shoulder thereby to limit the longitudinal movement and prevent rotation of the member.

2. A drill sharpening device comprising a flat base characterized by two substantially semi-circular sections of different radii and with their centers substantially coincident, a cylindrical body portion extending from the base with its axis normal to the plane thereof and in concentric relation to said sections, an abutment extending from the base alongside said body portion and beyond the end of the latter remote from the base, said body portion having an axial cylindrical recess that opens through its last mentioned end and the bottom wall of which is in the plane of the base, a cylindrical member slidably fitting said recess, said member having axial sockets in its ends and an axial bore connecting said sockets, a drill sharpening tool having a head that occupies the socket in the exposed end of said member and a shank that projects through said bore, the member having a radially disposed threaded hole that opens into said bore, a set screw threaded into said hole for engagement with the shank of the tool, a helical spring compressed between the bottom wall of the recess and the end wall of the socket in the adjacent end of said member, a threaded hole in the body portion in substantially parallel and closely spaced relation to the recess, the outer end of said hole being enlarged by a counterbore that opens through the end of the body portion remote from the base and laterally through the adjacent wall of the recess, the contiguous portion of the aforesaid member containing a part of said counterbore thereby to provide in said member a longitudinal groove and a shoulder at the bottom thereof, and a screw threaded into said hole and having a head extending into said groove and overhanging said shoulder thereby to limit longitudinal movement and prevent rotation of the member.

JOSEPH ADRIAN.
